(57) **CLAIM**

The ornamental design for a vehicle front lower valance, as shown and described.

DESCRIPTION

FIG. 1 is a front elevational view of a vehicle front lower valance, showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a top, front and left side perspective view thereof; and,

FIG. 7 is a bottom, front and left side perspective view thereof.

The ghosted or low contrasted portions of the vehicle front lower valance are provided for the purposes of illustrating portions that form no part of the claimed design.

1 Claim, 7 Drawing Sheets
